UNITED STATES PATENT OFFICE.

WILLIAM H. RIESS, OF CINCINNATI, OHIO.

TELEPHONE-RECEIVER.

1,286,885.

Specification of Letters Patent.

Patented Dec. 3, 1918.

Application filed January 29, 1917. Serial No. 145,159.

To all whom it may concern:

Be it known that I, WILLIAM H. RIESS, a citizen of the United States, residing at the city of Cincinnati, in the county of 5 Hamilton and State of Ohio, have invented certain new and useful Improvements in Telephone-receivers, of which the following is a specification.

The object of my invention is to provide 10 a telephone receiver which will, when taken off of the switch hook or hanger and placed upon some object, as a table, board, shelf or the like, always lie or assume a position that the mouth or trumpet end thereof will 15 be up or open and free to emit sound, when the telephone exchange wants to give notice to the user that his receiver is off of the switch or hook.

The telephone user cannot be reached by 20 the exchange if his receiver is resting mouth down upon a surface, as the sound is cut off and consequently, notice cannot be given, causing an expense to the telephone company on account of usage of electric current 25 and preventing the company from reaching the patron who has cut off his telephone and rendered it inoperative for the time being.

The object of my invention is to overcome 30 these objections and form and construct the receiver in such a manner, that when said receiver is laid down it will always "right itself" or tip so that the mouth or trumpet end of the receiver will be exposed and open. 35 I accomplish this by weighting and peculiarly forming the receiver so that it will always assume an upright position when laid down so that the mouth or trumpet end will always be exposed.

40 It is also, if desired, so constructed at the mouth or trumpet end that, if it is placed flat with the mouth end on the object on which it is resting, it will assist in tilting the same to an upright position.

45 In the accompanying drawings, forming part of this specification:

Figure 1, is a front elevation of a telephone instrument with my improved receiver hanging on the switch hook, or lever,

50 Fig. 2, is a similar view except that it is broken away and the receiver is hanging downward instead of extending outward, as in Fig. 1,

55 Fig. 3, is a plan view looking at mouth of receiver, the receiver shown however being

of a different form from that shown in Figs. 1 and 2,

Fig. 4, is a section on line 4—4 of Fig. 3, partly broken away, the receiver shown however being of a different form from that shown in Figs. 1 and 2,

Fig. 5, is a view in elevation of my new telephone receiver, being however of a different form from that shown in the other figures and

Fig. 6, is a view in elevation of the receiver standing on a flat surface, dotted lines showing it lying on its side, before it has assumed an upright position, and being of a form combining the features of the receiver shown in Figs. 1 and 5.

The telephone instrument is marked 1, the cut out or switch hook 2, the receiver 3 and the wires on the receiver 4, the mouth piece of the receiver is 5 and the base or heel end of the receiver is marked 6.

On the mouth part of the receiver 3, I place a projection or attachment 7 and on the face of the mouth rim I place spring actuated projections or buttons 8. They 80 have a hollow shank 9 which enters a recess 10 in the mouth part, a spring 12 entering into said hollow shank.

It will be noticed that the receiver is widest and largest at the mouth part and 85 tapers downward in cone shape to base 6 where it is weighted, the weight being designated by numeral 13, (see particularly Fig. 5.)

I also provide on the receiver, cut away 90 parts as 30; these parts may be formed rounded, flat or wedge shaped or they may be of any other desired contour so that the receiver may be quickly and conveniently hung up on the switch lever or cutout, and 95 if this cutout or switch is of any other form than herein shown the receiver may be so shaped, as may also the projections, that they will be best adapted to coact therewith.

The projections 7 and 8 assist in tilting 100 the receiver 3 inasmuch as the said receiver cannot be placed down on the mouth end flat, so they assist in tilting said receiver to an upright position and at the same time act as hangers for suspending the receiver at 105 any angle desired on the switch hook 2; it will be also noted that even if the receiver 3 did not tilt to an upright position, the projections would still keep the trumpet end or mouth open to emit sound and give notice 110

to the user that the receiver is off of the switch hook.

The receiver may be made of any desired shape and weighted in any desired manner to best enable it to quickly assume an upright position as shown. The weight on the receiver may be made integral therewith or separately and may be of any material.

10 In Figs. 1 and 2 part 8 is not shown, as in these figures a part 7 is shown, which answers the double purpose of a hanger and also assists in holding the receiver mouth off of the object upon which the 15 receiver is resting, and part 7 is not shown in Fig. 3, as in this figure I show part 8. I do not show parts 7 and 8 in Fig. 5, as in this figure it is not necessary to show them, as the receiver can be tilted without 20 them on account of the peculiar shape given to the receiver and part 8 is not shown in Fig. 6, as practically the same receiver is shown as is illustrated in Figs. 1 and 2.

The construction and shape of my tele-

phone receiver enables the user to handle 25 it more readily and conveniently, in either taking the same off or placing it on the switch or cut out and it can also be held at the ear more satisfactorily and can be handled more rapidly.

30 What I claim as new and my invention and desire to secure by Letters Patent is:

1. A telephone receiver peculiarly shaped and weighted rendering it capable of automatically assuming a position that the 35 mouth end thereof will always be exposed, when said receiver is laid down.

2. A telephone receiver shaped and weighted rendering the same capable, when 40 laid down, of automatically assuming a pre-determined position that the mouth of said receiver will always be exposed.

Witness my hand at Cincinnati, Ohio, January 26, 1917.

WILLIAM H. RIESS.

Witnesses:

H. E. CARSTENS,
JOHN W. STREHLI.
